UNITED STATES PATENT OFFICE.

HENRY J. VETTER, OF NEW YORK, N. Y.

BOX ATTACHMENT.

Application filed October 6, 1924. Serial No. 741,877.

To all whom it may concern:

Be it known that I, HENRY J. VETTER, a citizen of the United States, residing at New York city, in the county of New York and 5 State of New York, have invented certain new and useful Improvements in Box Attachments, of which the following is a specification, reference being had to the accompanying drawings.

10 This invention relates to certain improvements in box attachments and has relation more particularly to an attachment especially designed and adapted for use in connection with a box comprising a hinged cover 15 and it is an object of the invention to provide a novel and improved attachment which may be employed to maintain the lid of the box in an open position for the ready display of the contents of the box and at the 20 same time to permit the inner face of the box cover to be employed for advertising or other purposes.

Another object of the invention is to provide a novel and improved attachment of 25 this general character which is adapted, when the box lid is in closed position, to straddle the upper marginal portion of a wall of the box body so that the attachment will be entirely concealed and will in no way 30 offer any obstruction or hindrance to the requisite or desired closing of the cover.

The invention consists in the details of construction and in the combination and arrangement of the several parts of my improved box attachment whereby certain important advantages are attained and the device rendered simpler, less expensive and otherwise more convenient and advantageous for use, as will be hereinafter more fully set 40 forth.

The novel features of my invention will hereinafter be definitely claimed.

In order that my invention may be the better understood, I will now proceed to describe the same with reference to the accompanying drawings, wherein:—

Figure 1 is a view in perspective illustrating attachments constructed in accordance with an embodiment of my invention and in 50 applied position for maintaining the box cover in raised position;

Figure 2 is a fragmentary sectional view illustrating one of my improved attachments in applied position and in side elevation 55 with the cover raised;

Figure 3 is a fragmentary view partly

in section and partly in elevation showing the box cover in closed position and illustrating in plan the location of the attachment when the box cover is in such position; 60

Figure 4 is a fragmentary sectional view taken substantially on the line 4—4 of Figure 3.

As disclosed in the accompanying drawings, B denotes a box body having coating 65 with its upper or open face the hinged box cover C, said cover, as herein disclosed, having its outer or free longitudinal margin and its end margins defined by the flanges 1 which, when the cover is closed overlie or 70 overlap the adjacent walls of the box body B.

My improved attachment as herein disclosed, comprises a relatively long member 75 A in the form of an inverted U in cross section and having the extremities of its side walls 2 extending a desired distance beyond the intermediate or connecting portion 3 whereby each end of the member A is provided with a pair of outstanding spaced 80 ears 4.

When the box cover C is in closed position with respect to the box body B, the attachment A straddles the upper marginal portion of an end wall 5 of the box from above 85 with the intermediate portion 3 of the member A in close contact with the upper free edge of said wall so that with the cover C in closed position, the attachment offers no undue hindrance or obstruction thereto. The 90 ears 4 remote from a hinged margin of the cover C are pivotally connected to the upper marginal portion of the wall 5 by a holding member 6 which may be as desired but which, as herein disclosed, is a well-known 95 type of split shank fastening member. This member 6 is passed through the wall 5 and also through suitable openings 7 provided in said ears 4.

When the cover C is raised, the ears 4 at 100 the opposite end of the member A have fitted therebetween the end flange 1 of the cover C, said ears being attached to said flange 1 by the holding member 8 which may also be as desired but herein illustrated as of the same character as the holding member 6. These second ears 4 are also provided with the openings 9 to permit the requisite application of the holding member 8.

While in practice a single attachment A 110 will suffice to maintain the cover C in its desired raised position, yet it may be preferred

to employ two of such attachments as illustrated in the accompanying drawings, said attachments being associated with the end walls 5 of the box body B and the end flanges 1 of the cover C.

Under some conditions it may not be essential that the holding members 8 be employed but their use is preferred as it assures a positive maintenance of the cover C in desired raised position.

With the use of my improved attachment or attachments the cover C is positively held in a desired raised position to effect a display of the contents of the box body B and also to facilitate the use of the inner face of the cover C for advertising or other display.

It is also to be noted that no particular skill is required in applying my improved attachments in desired position as the opposite end portions thereof are in duplicate.

It will also be understood that the angle at which the cover C will be held open by my improved attachment will depend upon the distance between the connection of such attachment with a side wall 5 with respect to the hinged connection between the box cover C and the box body B together with the length of the intermediate portion 3 of the attachment.

From the foregoing description it is thought to be obvious that a box attachment constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:—

1. The combination with a box body and a hinged cover therefor, a margin of the cover having a flange adapted to overlie a wall of the box body when the cover is in closed position; a member substantially U-shaped in cross section and adapted to straddle the upper marginal portion of said wall of the box body from above, means for

pivottally connecting an end portion of said member to such wall, the opposite end portion of the member being provided with spaced ears to receive therebetween the flange of the box cover when the box cover is in open position.

2. The combination with a box body and a hinged cover therefor, a margin of the cover having a flange adapted to overlie a wall of the box body when the cover is in closed position; a member substantially U-shaped in cross section and adapted to straddle the upper marginal portion of said wall of the box body from above, means for pivottally connecting an end portion of said member to such wall, the opposite end portion of the member being provided with spaced ears to receive therebetween the flange of the box cover when the box cover is in open position, and means for connecting said ears and flange.

3. As a new article of manufacture, a box attachment for maintaining a hinged box lid in raised position comprising a substantially U-shaped member adapted to straddle a wall of the box body from above, the opposite ends of the member being provided with outstanding spaced ears, the ears at one end of the member being adapted to be pivottally connected with the box body, the ears at the opposite end of the member being adapted to receive a flange of a box cover therebetween.

4. The combination with a box body and a hinged cover therefor, a margin of the cover having a flange adapted to overlie a wall of the box body when the cover is in closed position; a member substantially U-shaped in cross section and adapted to straddle the upper marginal portion of said wall of the box body from above, means for pivottally connecting an end portion of said member to such wall, the opposite end portion of the member being provided with spaced ears to receive therebetween the flange of the box cover when the box cover is in open position, the intermediate portion of the member having close contact with the free edge of the wall when the member is free of the box cover, or swung downwardly toward the wall.

In testimony whereof I hereunto affix my signature.

HENRY J. VETTER.
